UNITED STATES PATENT OFFICE.

JOSEPH R. BLAINE, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

RELOADING FEEDER.

1,388,161.

Specification of Letters Patent. Patented Aug. 23, 1921.

Application filed April 27, 1917, Serial No. 164,942. Renewed January 17, 1921. Serial No. 437,374.

To all whom it may concern:

Be it known that I, JOSEPH R. BLAINE, a citizen of the United States, and resident of Oak Park, in the county of Cook and State 5 of Illinois, have invented certain new and useful Improvements in a Reloading Feeder, of which the following is a specification.

My invention relates to printing presses and particularly to means for feeding and 10 reloading a pile of sheets.

An object in the present invention is to provide means whereby the usual delays incident to the reloading of a feed pile may be avoided. To this end I have provided a 15 plurality of endless chains together with means for actuating the same in unison. These chains depend in a long loop at a point near the corners of the table. Clutch members are provided on the table adjacent 20 the chains the clutches being so constructed as to enable engagement with the chains at any link thereof. The advantage of any such construction is in that when the pile is nearly exhausted another pile carried by 25 a second table may be positioned beneath the first and be ready for instant engagement with the endless chains. When the upper pile is exhausted the table may be quickly 30 disengaged from the chains and the operations continued uninterruptedly.

Another object is to provide means in connection with the table for adjusting the pile thereon in order that it may be accurately positioned as required when automatic feeding mechanism is employed.

The invention will be more readily understood by reference to the accompanying drawings, wherein,

Figure 1, is a side elevation of pile feeding 40 means constructed in accordance with my invention;

Fig. 2 is a view taken at right angles to that of Fig. 1, and showing one corner only of the arrangement;

Fig. 3 is an enlarged side elevation of the 45 chain clutch;

Fig. 4 is a sectional view on the line 4—4 of Fig. 3;

Fig. 5 is an enlarged view, partly in section, showing the means employed for adjusting the table, and,

Fig. 6 is a view taken at right angles to that of Fig. 5.

In the drawings it will be seen that I provide a plurality of standards 10, on the

upper ends of which are supported the paper feeding means indicated diagrammatically at 11, 12. The standards 10, may be in the form of large tubes or cylinders and serve to support arms 13. The arms are adapted 60 for oscillation within the limits defined by the stops 14. By this means the arms may be swung out of the position shown in Fig. 1 to permit of the entrance of a truck carrying a new pile. The arms 13, rest upon collars 65 15, which carry the stops 14, the collars being adapted to be secured at different points in the height of the standards 10. Inasmuch as the weight imposed on the arms when a full pile is to be supported 70 thereby is great, I have provided jacks 16, which directly transmit the load to the floor or a similar support. These jacks may be merely in the form of a threaded standard 75 engaging the outer ends of the arms. The pile of paper indicated at 17, rests directly upon a table 18, which is in turn supported by the I-beams 19. In the channels of the I-beams at the ends thereof are mounted the clutch members shown in Figs. 3 and 4. 80 These members comprise a body portion 20, having a slot 21, and an end member 22, having a chain-shaped side opening 23. The opening 23, is intersected by downwardly 85 projecting lugs 24. The arrangement of the recesses is such that a chain readily engages the same but cannot be disengaged without first lifting the clutch member. This obviates the possibility of accidental disengagement of the lifting element and the pile 90 table.

The lifting elements are in the form of endless chain conveyers 25, one of which is provided at each corner of the table and which depend in the form of a long loop. 95 The chains at their upper ends pass around suitable sprockets 26, mounted on a long shaft 27, for movement in unison in the same direction of the corresponding portions of every chain. Manual or power means may 100 be employed for actuating the shaft, no such means being here shown.

It is sometimes necessary that the table be adjusted relatively to the supporting beams 105 19, and as the weight is great, I provide screw means such as shown in Figs. 5 and 6, for accomplishing the desired result. The means comprise a block 28, having tapered lips 29, on the under surface thereof, adapted to fit over the flanges 30, of the beam. A 110

dowel pin 31, is carried by the block at a point near the rear edge of the block; that is, at the point where there is the greatest space between the lips 29 and the body of the block. This pin is adapted to engage one of the recesses 32, in the top of the beam. A bolt 33, passes through the block and engages the side of the table 18. To engage or disengage the adjusting means from the beam it is necessary only to rock the same on its front edge. This will disengage the dowel and permit the block to be slid longitudinally of the beam.

The advantages in this construction arise from the fact that a pile may be readily attached to the lifting chains and be elevated as required until the pile is nearly exhausted. In the meantime a new pile may be moved by a truck to a point directly beneath the first pile, whereupon the truck may be removed and the pile supported on the arms 13. While in this position it will be positioned accurately by the means just described. During that time the clutch members 20, will be in a retracted position as shown in the lower portion of Fig. 2; that is, where the chain is not engaged therewith. This is accomplished by sliding the clutch member longitudinally of the beam. It will be noted that the bolt 34 serves merely to hold the parts in proper relation, no clamping action being necessary. When the upper pile is exhausted the table is disengaged by disengaging the clutch members whereupon the chain is caused to engage the clutch members of the lower table and the operation of the printing press may continue without unnecessary delay.

While I have described the construction as particularly adapted for use in connection with a feeding table for printing presses, it is apparent it might be employed in connection with many other forms of devices which require the delivery thereto of piles of paper. It is apparent also that many of the advantages herein described would accrue to the use of the device on the discharge table and the appended claims should be construed with that understanding.

50 I claim:

1. A lifting conveyer for pile tables, comprising in combination, a plurality of chains, and clutches carried by the table, said clutches having open sided chain-shaped recesses and downwardly projecting lugs for engaging any link of said chain, whereby a chain cannot be separated there-

from without first raising the clutch member, substantially as described.

2. Pile feeding means, comprising in combination, a plurality of standards, swinging arms supported on the standards near the lower ends thereof, and means for lifting a pile between the standards, a second pile being adapted to be supported on said arms while said first pile is being lifted and means carried by said arms for serving as additional supports therefor, substantially as described.

3. Pile feeding means, comprising in combination, a plurality of standards, swinging arms supported on the standards near the lower ends thereof, a plurality of endless lifting elements depending between the standards, a table adapted to be engaged by said elements, and a second table adapted to be supported on said arms and to be engaged by said elements and means carried by said arms for serving as additional supports therefor, substantially as described.

4. Pile feeding means, comprising in combination, a plurality of standards, swinging arms supported on the standards and adapted to be swung into and out of supporting position, and a jack on each of said arms for transmitting weight directly to a support at points other than at said standards, substantially as described.

5. A feeding means for printing presses, in combination, a plurality of endless conveyers, means for causing the movement thereof in unison in the same direction, a pile table, clutches carried by the table and constructed to operatively engage the conveyers at any point in the length thereof, and to be disengaged therefrom when said conveyers reach the end of travel thereof in one direction, a second pile table arranged to engage said conveyers while said first table is in engagement therewith and at a point below said first table, means for supporting said table in position to be engaged by said conveyers, and means for adjustably positioning the pile on the table, said adjustment means being carried by the table and arranged to maintain said pile in adjusted position during the movement of the table by the conveyers.

Signed at Chicago, Illinois, this 24th day of April, 1917.

JOSEPH R. BLAINE.
